United States Patent

Des. 240,617
Patented July 20, 1976

240,617

BUILDING

A. F. R. Svensson, 5655 Old National Highway,
College Park, Ga. 30349

Filed Sept. 11, 1974, Ser. No. 504,865

Term of patent 14 years

Int. Cl. D25—03

U.S. CL. D25—10

FIG. 1

FIG. 2

FIG. 3

FIG. 4

FIG. 5

FIG. 1 is a view in top plan of a building showing my new design;

FIG. 2 is a view in side elevation thereof looking upwardly with respect to FIG. 1;

FIG. 3 is a side elevational view thereof showing the side opposite that seen in FIG. 2;

FIG. 4 is a side elevational view thereof as seen from the right side of FIG. 2; and

FIG. 5 is a side elevational view thereof as seen from the left side of FIG. 2.

The bottom, not shown, is devoid of ornamentation.

I claim:

The ornamental design for a building, substantially as shown and described.
